[57] CLAIM

The ornamental design for broom handle with bumpers, as shown and described.

DESCRIPTION

FIG. 1 is a top environmental perspective view of broom handle with bumpers showing my new design;

FIG. 2 is a bottom perspective view thereof;

FIG. 3 is a top view thereof;

FIG. 4 is a front elevational view thereof with the rear view and the right and left side elevational views being mirror images thereof; and,

FIG. 5 is a bottom view thereof.

The broken line showing of a broom head in FIG. 1 is for illustrative purposes only and forms no part of the claimed design.

The handle is shown broken away to indicate indeterminate length.
